(57) **CLAIM**

The ornamental design for a cooling fan, as shown and described.

DESCRIPTION

FIG. 1 is a front and top perspective view of a cooling fan, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is another perspective view thereof, shown in an alternative position.
 The broken lines in the figures illustrate portions of the cooling fan that form no part of the claimed design.**1 Claim, 9 Drawing Sheets**FIG. 1

FIG. 2

FIG. 3

FIG. 4

FIG. 5

FIG. 6

FIG. 7

FIG. 8
